Patented Aug. 11, 1914.

UNITED STATES PATENT OFFICE.

LINUS TERRY FURNAS, OF LIMA, OHIO.

DRESS-FORM.

1,107,055.

Specification of Letters Patent.

Patented Aug. 11, 1914.

Application filed June 6, 1913. Serial No. 772,075.

To all whom it may concern:

Be it known that I, LINUS TERRY FURNAS, a citizen of the United States, and a resident of Lima, in the county of Allen and State 5 of Ohio, have invented a new and Improved Dress-Form, of which the following is a full, clear, and exact description.

The object of the invention is to provide a new and improved dress form to be worn 10 beneath corset covers, skirts, and other garments with a view to rectify deficiencies in the body of the wearer, and arranged to permit the user to accurately draw up the ruffles after washing the garment with a view to 15 correctly shirr the ruffles to fit the garment.

In order to accomplish the desired result, use is made of a flounce provided with hems, each containing a loop string doubled up to form a loop and secured at its end to one 20 end of the hem, and a draw-string likewise doubled up and passing through the loop of the loop string, one end of the draw-string being secured to the other end of the hem, and the loose end of the draw-string extending 25 ing out of the hem at this end.

A practical embodiment of the invention 30 is represented in the accompanying drawings forming a part of this specification, in which similar characters of reference indicate corresponding parts in all the views.

Figure 1 is a face view of the dress form looking at that side next to the garment to which it is attached, part of the flounce being 35 shirred and part of the flounce being broken out; Fig. 2 is an enlarged face view of a portion of a flounce and the means for shirring the flounce, parts being shown broken away. Fig. 3 is an enlarged cross section of the dress form on the line 3—3 40 of Fig. 1; and Fig. 4 is a similar view of the same on the line 4—4 of Fig. 1.

In reshirring the ruffles after the garment is washed the user often has considerable difficulty in correctly shirring the 45 ruffle to provide the desired fullness, the ruffle being either shirred too much or not enough. The body or foundation A of the dress form, which is shown in dotted lines in Fig. 1, may be made of muslin or any other 50 suitable woven fabric, netting or open mesh material, and is provided with a series of flounces B, the upper edges of which are secured at one end only to the outer surface of the body A, these flounces extending in a se-

ries across the upper front portion of the 55 garment, and each consisting of a foundation piece C to which are secured the upper edges of flaps D, these flaps being disposed upon the inner surface of the foundation piece C and extending to 60 toward the garment or body A. Each of the flounces B is provided with hems F, preferably one at the top and one at each junction of the flap D with the piece C, and within each hem F are arranged a loop string G 65 and a draw-string H. The loop string G is doubled up to form a loop and its ends are secured by stitches I or other means to the corresponding end F' of the hem F, and the doubled-up loop string G is of a length cor 70 responding approximately to the length of the flounce B after being shirred. The draw-string H is also doubled up and passes through the loop G and one end of the draw-string H is secured by stitches J or 75 other means to the other end F' of the hem F. The free end H' of the draw-string H extends through the open end F' of the hem F to the outside thereof. Now when the flounce B is flattened out and it is desired 80 to shirr the flounce, it is only necessary for the user to pull on the free end H' of each draw-string H so as to shirr the ruffle along the loop string G, it being understood that on pulling on the free end H' of the draw- 85 string H the loop string G is drawn through the hem F toward the end F', and when the latter point is reached the ruffle is shirred on the loop string G. From the foregoing it will be seen that the length of the shirred 90 ruffle corresponds to the length of the loop string G, which is the required length to shirr ruffle to proper fullness. The draw-strings H of the adjacent flounces B are tied into bows H', as plainly indicated in 95 Fig. 1, so as to hold the flounces in shirred positions, it being seen that in order to permit this to be done, the flounces are secured in pairs across the garment or other foundation, with the draw strings of each pair 100 extending inwardly toward one another.

From the foregoing it will be seen that the user of the garment after washing the same can quickly and correctly shirr each ruffle to obtain the desired fullness and without 105 danger of shirring the ruffles too much or not sufficiently.

Although I have shown and described a

particular form of flounce, it is evident that I do not limit myself to any special construction of the flounce as the sets of strings G and H can be used in the hems of any 5 flounce for the purpose mentioned.

Having thus described my invention, I claim as new and desire to secure by Letters Patent:

1. A dress form provided with a flounce 10 having a guide, a loop string within the said guide and doubled up to form a loop, the ends of the loop string being secured to one end of the flounce, and a draw-string extending within the said hem and doubled 15 up, the draw-string passing through the loop of the loop string and having one end secured to the other end of the flounce, the other and free end of the draw-string extending beyond the last-mentioned end of 20 the flounce.
2. A dress form, comprising a foundation, a flounce secured at one upper corner to the said foundation and overlying the same, the flounce being provided with a longitudinally-extending hem reaching from one end 25 of the flounce to the other end, a loop string extending within one portion of the hem and doubled up to form a loop, the ends of the loop string being fixed in the corresponding end of the hem, and a draw string extending 30 in the other portion of the hem and doubled up, the draw string passing through the loop of the loop string and having one end secured to the other end of the hem, the loose end of the draw-string extending 35 through the end of the hem to the outside thereof.
3. A dress form provided with a flounce having a hem, a loop string within the said 40 hem and doubled up to form a loop, the ends of the loop string being secured to one end of the hem, and the length of the loop string corresponding to the length of the ruffle 45 when shirred, and a draw-string extending within the said hem and doubled up, the draw string passing through the loop of the loop string and having one end secured to the other end of the hem, the loose end of 50

the draw-string extending through the end of the hem to the outside thereof.

50

4. A dress form, comprising a foundation, flounces secured at one upper corner to the said foundation and overlying the same, each flounce being provided with a longitudinally-extending hem reaching from one end 55 of the flounce to the other end, a loop string extending in one portion of the hem and doubled up to form a loop, the ends of the loop string being fixed in the corresponding end of the hem, the length of the doubled-up 60 loop string determining the length of the shirred ruffle, and a draw-string extending in the other portion of the hem and doubled up, the draw-string passing through the loop of the loop string and having one 65 end secured to the other end of the hem, the loose end of the draw-string extending through the end of the hem to the outside thereof the said flounces being arranged in pairs on the said foundation, and the flounces 70 of each pair having the free ends of their drawstrings extending toward one another to permit them to be tied to one another when the flounces are shirred.

70

5. A dress form comprising a foundation, 75 flounces attached to the foundation, and shirring and limiting means on each flounce for shirring the same, comprising co-operating members for limiting the shirring to form a ruffle of the length of one of said 80 members.

80

6. A dress form comprising a foundation, flounces attached to the foundation, and shirring and limiting means on each flounce for shirring the same, comprising interengaging loop members for limiting the shirring to form a ruffle of the length of one of 85 the loops.

85

In testimony whereof I have signed my name to this specification in the presence of 90 two subscribing witnesses.

LINUS TERRY FURNAS.
